his ATTORNEY.

UNITED STATES PATENT OFFICE.

GUSTAV FALK, OF NEW YORK, N. Y.

HAND OF LEAF-TOBACCO.

SPECIFICATION forming part of Letters Patent No. 476,943, dated June 14, 1892.

Application filed November 3, 1891. Serial No. 410,708. (No model.)

To all whom it may concern:

Be it known that I, GUSTAV FALK, of the city, county, and State of New York, have invented a new and useful Improvement in 5 Hands of Leaf-Tobacco, of which the following is a full, clear, and exact description, reference being had to the accompanying drawings, forming part thereof, and in which—

Figure 1 is a plan view of a collection of 10 ordinary hands of tobacco. Fig. 2 is a plan view of a collection of my improved hands. Fig. 3 is a cross-section of one of my improved hands on the line of the stitches *e*.

Like reference-letters refer to like parts 15 throughout the drawings.

My invention relates to an improved tobacco-hand; and it consists in the construction thereof, as hereinafter described, and distinctly pointed out in the claim.

The object of my invention is to produce a tobacco-hand which will obviate the necessity 20 of packing and transporting the objectionable and useless butt-ends, which when so packed and transported form in hard masses and injure the overlying and underlying hands or 25 bundles. By my improved hand I am enabled to pack and ship the tobacco with greater safety and eliminate the useless and objectionable matter therefrom and occupy much 30 less room than heretofore.

Fig. 1 shows a collection of ordinary hands with the butt-ends attached thereto, and in which *a* represents the body portion, and *b* the butt-ends attached thereto. *c* designates the means for tying or fastening generally used 35 in an ordinary hand.

In Fig. 2 is shown a collection of my improved hands, each hand consisting of leaves placed flat upon each other and having the butt-ends removed on the line *d* of Fig. 1 and 40 being stitched transversely across the body portion, as shown at *e*, which stitching keeps the various leaves in their respective positions, forming a flat compact mass without danger of injury from hard and objectionable substances. 45

Having described my invention, what I claim, and desire to secure by Letters Patent, is—

A hand of leaf-tobacco separated from the 50 butt-ends, arranged together in a flat form, and secured together by stitching, substantially as described.

GUSTAV FALK.
